UNITED STATES PATENT OFFICE.

ADOLPHUS M. SHENK, ANDREW SALTZER, AND LOUIS SALTZER, OF CALEXICO, CALIFORNIA; SAID ANDREW SALTZER AND SAID LOUIS SALTZER ASSIGNEES OF ONE-SIXTH OF THE ENTIRE RIGHT TO SAID SHENK.

WRENCH.

1,394,225.

Specification of Letters Patent.

Patented Oct. 18, 1921.

Application filed January 3, 1921. Serial No. 434,699.

To all whom it may concern:

Be it known that we, ADOLPHUS M. SHENK, ANDREW SALTZER, and LOUIS SALTZER, citizens of the United States, residing at Cal-
5 exico, in the county of Imperial and State of California, have invented new and useful Improvements in Wrenches, of which the following is a specification.

Our invention relates to new and useful
10 improvements in wrenches of the general type employing fixed and movable jaws, and which are generally used for the manipulation of bolts and nuts and for rotating or for gripping and holding against rotation
15 objects such as pipes, rods and the like.

The principal objects of our invention are to provide a relatively simple, strong and durable wrench, and to construct the movable jaw and its support or carrier so that
20 it can be disengaged from the shank of the wrench, shifted toward or away from the fixed jaw so as to adjust the width of the opening between the jaws to the work or object that is to be engaged, and to reengage
25 said movable jaw with said shank and effectively lock it thereto after adjustment relative to the fixed jaw.

With the foregoing and other objects in view, our invention consists in certain novel
30 features of construction and arrangement of parts that will be hereinafter more fully described and claimed, and illustrated in the accompanying drawings in which:

Figure 1 is a front, elevational view of a
35 wrench constructed in accordance with our invention.

Fig. 2 is a side elevational view of the wrench.

Fig. 3 is an enlarged vertical section taken
40 approximately on the line 3-3 of Fig. 1.

Referring by numerals to the accompanying drawings which illustrate a practical embodiment of our invention, 10 designates the body or shank of the wrench, the same
45 being formed from a straight bar of metal, the lower end of which is formed into a handle 11, and the upper end being provided with an integrally formed, laterally projecting jaw 12. The under side of this jaw may
50 be substantially flat, and provided with small teeth or corrugations, as illustrated in Fig. 1. The underside of said jaw may be provided with an angular recess 13 of such shape as to engage the angular faces of a

hexagonal member such as a nut or the head 5 of a bolt.

One edge of the shank 10 below fixed jaw 12 is provided with a series of transversely disposed teeth 14, and adapted to engage therewith are similar teeth 15 that are 60 formed on the inner face of a wedge-shaped block 16, the latter carrying at its upper end an integrally formed, laterally projecting jaw 17. This movable jaw is adapted to co-operate with jaw 12 to engage a member 65 that is to be gripped and held or rotated, and this upper face may be flat or it may be notched or recessed, as illustrated in Fig. 1.

A wedge-shaped block 16 is loosely ar- 70 ranged in a tapered pocket 18 that is formed in the upper portion of a sleeve 19, which latter is substantially square or rectangular in cross section, and adapted to slide freely upon shank 10.

Formed in the inclined wall 20 in front of the pocket 18 is a vertically disposed slot 21, and passing therethrough is a pin or screw 22 that is seated in the lower portion 80 of wedge-shaped block 16. In the event that member 22 is in the form of a screw, a washer such as 23 is positioned between the head of said screw and the outer face of wall 20.

When movable jaw 17 is adjusted to the 85 desired position and locked in this position to shank 10, the various movable parts occupy the positions illustrated by solid lines in Fig. 3, and, by virtue of the position of the wedge-shaped block 16 that carries the 90 movable jaw in the tapered recess 18, said block is firmly held so that its teeth 15 engage certain of the teeth 14, thereby firmly holding the movable jaw in its adjusted position. To enable the movable jaw to be ad- 95 justed in either direction upon the shank, sleeve 19 is manually engaged and forced downwardly upon shank 10, and such action moves the inclined wall 20 away from the outer face of wedge block 16 a sufficient dis- 100 tance to permit the teeth 15 of said wedge block to be disengaged from the teeth 14, on the shank, after which the sleeve and jaw carrying block 16 can be shifted lengthwise upon the shank, and consequently increasing 105 or decreasing the space between jaws 12 and 17. After proper adjustment has been effected, sleeve 19 is moved downwardly rela-

tive to wedge block 16 and shank 10, and such movement causes inclined wall 20 to bear against the outer face of said wedge block, and consequently bringing about a firm and substantially interlocking engagement between the teeth 15 and 14.

A wrench of our improved construction is comparatively simple, is capable of being easily and cheaply produced, is "quick acting" in that its movable jaw can be readily adjusted toward or away from the fixed jaw, and said wrench is very effective in performing its intended functions.

It will be readily understood that minor changes in the size, form and construction of the various parts of our improved wrench may be made and substituted for those herein shown and described without departing

from the spirit of our invention, the scope of which is set forth in the appended claim. 20

We claim as our invention:

A wrench comprising a shank, a sleeve 25
slidable thereon and having a tapering
pocket and a shank engaging portion ex-
tending beyond the same to form a hand
hold, a wedge block in said pocket adapted
to adjustably clamp said sleeve to said shank,
said sleeve being slotted, and an operating
member projecting from said block through
said slot and conveniently positioned with 30
relation to said hand hold.

In testimony whereof we have signed our
names to this specification.

ADOLPHUS M. SHENK.
ANDREW SALTZER.
LOUIS SALTZER.
